ADAM LEROY SCHWAB, OF NEW PHILADELPHIA, OHIO

INGOT-FEEDER CLAMP AND SHOULDER SUPPORT

Application filed April 13, 1929. Serial No. 354,890.

When employing the usual ingot feeders or "hot tops", there is severe danger of breakage under expansion, with consequent danger of portions of the broken feeder falling into the ingot mold and producing an inferior ingot. To prevent such occurrences in case the feeder should crack, it is now customary to wrap suitable wire around said feeder prior to the pouring operation, but it is the aim of the present invention to provide a new and improved clamp to surround the feeder, which clamp will overcome the necessity of using wire or the like and may be quickly and easily applied or released.

The feeders or "hot tops" now in common use are made of fire clay and have molded on their outer faces lugs which rest on top of the ingot mold and thus limit the movement of the feeder into the mold. The present invention in addition to serving as a clamp to hold the parts of a cracked feeder together, takes the place of the usual supporting lugs on the feeder and thus serve a twofold purpose, namely, as a clamp and as an adjustable supporting shoulder for the feeder.

In carrying out the above end, a further aim is to provide a clamp which is well ventilated to prevent overheating and one in which provision is made for the necessary expansion incident to the pouring operation.

The clamp embodies a transversely split band to surround the feeder and a still further aim is to provide a clamp for connecting the ends of said band, said clamp embodying spring means which acts not only to hold it in operative position, but permits separation of the band ends under expansion of the feeder.

With the foregoing in view, the invention resides in the novel subject matter herein-after described and claimed, description being accomplished by reference to the accompanying drawing.

Fig. 1 is a side elevation of a portion of an ingot feeder and the improved clamp thereon.

Fig. 2 is a horizontal sectional view on line 2-2 of Fig. 1.

Fig. 3 is a vertical sectional view on line 3-3 of Fig. 2.

Fig. 4 is a top plan view showing the clamp in open position.

The drawings above briefly described illustrate the preferred form of construction and while such construction will be herein specifically explained, variations may be made within the scope of the invention as claimed.

B on the drawings denotes the band as a whole, said band being formed of any desired number of sections S of any desired shape, according to the shape of the ingot feeder F which the band B is to surround. In the present showing, only two sections S are disclosed and they are yieldably connected by a connection C hereinafter described, and the ends of the band B are releasably connected with each other by a clamp C' whose details will also be explained. Upon release of the clamp C', the connection C and any other similar connections which the device may embody if of more than two-section construction, will act as a hinge as will be clear from Fig. 4, permitting outward swinging of the sections S for application to or removal from the feeder F. Upon tightening of the clamp C', the band B is tightly held around the feeder F and upon expansion of the latter incident to the pouring operation, portions of said connection C and clamp C' will expand to any required extent. In case the feeder F should crack, the band B will tightly hold it in shape and will not permit any portions thereof to fall into the ingot mold.

In addition to performing this function, the band B limits the insertion of the feeder F into the ingot mold M, by resting upon the upper edge of the latter, and to insure proper positioning of said band upon the feeder, any desired means may be employed. Pins P are here shown insertible into openings O in the feeder F, said pins being loosely connected with the band B by chains or the like.

The connection C embodies two lugs 5-6 secured to the adjacent ends of the sections S and projecting outwardly therefrom, said lugs having openings 7 through which a fastener such as a bolt 8 passes slidably. This

bolt is provided with a head or other shoulder 9 abutting the outer side of the lug 5 and is equipped with another shoulder such as a nut 10 spaced outwardly from the lug 6. A coiled compression spring 11 surrounds the bolt 8 between the lug 6 and the shoulder or nut 10. While this construction normally moves the sections S inwardly toward each other, it permits opposite movement of said sections under expansion of the feeder F. Then too, due to the looseness with which the bolt 8 is received in the openings 7, the lugs 5-6 may angle upon the bolt, allowing the entire connection C 15 to constitute a hinge as seen in Fig. 4, when the clamp is opened and closed.

The clamp C' embodies two spaced hooks 12 secured to one end of the band B, an apertured lug 13 secured to the other end 20 of this band, a link 14, a spring 15 associated with said link, and a lever 16 fulcrumed to said link and engageable with the hooks 12. The link 14 extends across the split between the ends of the sections S and one end of this link is outwardly bowed around the hooks 12 as seen at 17. The other end of this link is in the form of a shank 18 passing loosely through the aperture 19 of the lug 13, said shank being provided with a nut or other shoulder 20 spaced outwardly from said lug. The spring 15 is of coiled compression form and it surrounds the shank 18 between the nut or the like 20 and the lug 13. The bowed end portion 17 of link 14 is preferably bifurcated and the lever 16 is pivoted at 21 near one of its ends, between the furcations of said link end, said end of the lever being provided with oppositely projecting studs 22 engageable with the hooks 12 to provide the fulcrum about which the lever is moved. When lever 16 is swung inwardly to the position shown in Fig. 2, the pivot 21 is slightly beyond a straight line passing through the center of the opening 19 and the studs 22, so that the spring 15 will hold the lever in this position. Then too, this spring yields under expansion of the feeder F and co-operates with the spring or springs 11 in allowing the necessary expansion of the band B. When lever 16 is swung outwardly as in Fig. 4, the ends of the band are disconnected from each other and consequently said band is in readiness for quick and easy application to or removal from the feeder F. If desired, a length of pipe or the like 23 may be slipped over the outer end of the lever 16 for operating it from a distant point at which the heat is not so intense as in immediate proximity to the feeder and mold.

The entire band B is provided throughout its inner circumference with a ventilating channel 24 and a plurality of openings 25 extend from this channel to the exterior of the band. Air may flow freely through

the channel and the openings 25 and consequently excessive heating of the band B with danger of warping the same, is prevented. Moreover, the channel-shaped form imparted to the band provides it with two side flanges whose edges will grip the usually uneven exterior of the feeder F, more effectively than a single wide surface.

It will be seen from the foregoing that a rather simple and inexpensive, yet an efficient, desirable and durable device has been provided for carrying out the objects of the invention. As above stated, variations may be made within the scope of the invention as claimed, in which connection attention is again invited to the fact that the band B may embody any desired number of sections S connected with each other by yieldable connections such as C. Moreover, the shape of the sections S may vary in accordance with the shape of the feeder to which the device is to be applied. Then too, various changes in size, proportion, materials, etc., may be resorted to within the scope of the claimed invention.

I claim:

1. An ingot feeder clamp comprising a transversely split band consisting of separate sections and circumferentially yieldable connecting means between said sections, and quick releasable clamping means for detachably connecting the ends of the band with each other, said connecting means acting also as hinge means to allow outward swinging of said sections upon disconnection of the band ends by release of said clamping means.

2. An ingot feeder clamp comprising a transversely split band consisting of separate sections, lugs projecting outwardly from said sections and having openings, a fastener passing loosely through said openings and having a shoulder abutting one lug and a second shoulder spaced outwardly from the other lug, and a coiled compression spring around said fastener between said other lug and said second shoulder; and clamping means for connecting the ends of the band with each other.

3. An ingot feeder clamp comprising a transversely split band consisting of separate sections, circumferentially yieldable connecting means between said sections and circumferentially yieldable clamping means for connecting the ends of the band with each other, said connecting means acting also as hinge means to allow outward swinging of said sections upon release of said clamping means.

4. An ingot feeder clamp comprising a transversely split band having an outwardly projecting apertured lug at one end and two outwardly projecting hooks at its other end, a link extending across the split of said band and having one end bowed around said hooks, the other end of said link passing loosely

through the aperture of said lug and having a shoulder outwardly spaced from the latter, a coiled compression spring surrounding said link between said shoulder and lug, and a clamping lever pivoted near one of its ends to said bowed end of said link, said end of the lever having lateral studs engaged with said hooks, whereby to clamp the band ends yieldably together upon inward swinging of said lever.

10 5. An ingot feeder clamp comprising a band having a ventilating channel in its inner side.

15 6. An ingot feeder clamp comprising a band having a ventilating channel in its inner side and ventilating openings from said channel to its exterior.

20 7. An ingot feeder clamp comprising a band consisting of separate sections and yieldable connecting means between said sections acting also as hinge means to allow outward swinging of said sections, a clamping lever mounted on one end of said band, and means on the other end of said band for engagement with said lever to therewith establish a band-tightening quick-releasable detachable connection between the band ends.

25 8. An ingot feeder clamp comprising a band consisting of separate sections and circumferentially yieldable connecting means between said sections; clamping means mounted on one end of said band and embodying a spring and a lever for stressing said spring, and means on the other end of said band for engagement with said lever to act as a fulcrum therefor when effecting the spring-stressing movement of said lever, whereby the band ends will be yieldably and detachably clamped together.

30 9. An ingot feeder clamp comprising a transversely split band, clamping means mounted on one end of said band and embodying a spring and a lever for stressing said spring, and means on the other end of said band for engagement with said lever to act as a fulcrum therefor when effecting the spring-stressing movement of said lever, whereby the band ends will be yieldably and detachably clamped together.

35 50 In testimony whereof I have hereunto affixed my signature.

ADAM LEROY SCHWAB.
